SECURITY DEVICE FOR MOBILE TRANSCEIVERS OR THE LIKE

Jimmy D. Wallace, 800 Beckford Court W.,
Hurst, Tex. 76053

Filed June 4, 1975, Ser. No. 583,581

Term of patent 14 years

Int. Cl. D8—08

U.S. Cl. D8—233

FIG. 1

FIG. 2

FIG. 3

FIG. 4

FIG. 5

FIG. 6

FIG. 7

FIG. 1 is a perspective view of my new design for a security device for mobile transceivers or the like, the broken lines being for illustrative purposes only.

FIG. 2 is a front view of the security device shown in FIG. 1;

FIG. 3 is a back view of the security device;

FIG. 4 is a top view of the security device;

FIG. 5 is a bottom view of the security device;

FIG. 6 is a right side view of the security device; and
FIG. 7 is a left side view of the security device.

I claim:

The ornamental design for a security device for mobile transceivers or the like, as shown and described.
